UNITED STATES PATENT OFFICE

JOSEPH SCHNEIDERMAN, OF CHICAGO, ILLINOIS

DESIGN FOR A PROTECTOR FOR A NURSING BOTTLE AND NIPPLE THEREOF

Application filed August 20, 1932. Serial No. 44,648. Term of patent 3½ years.

To all whom it may concern:

Be it known that I, JOSEPH SCHNEIDERMAN, a citizen of the United States, residing at 1809 South Trumbull Avenue, in the city of Chicago, county of Cook, and State of Illinois, have invented a new, original, and ornamental Design for a Protector for a Nursing Bottle and Nipple Thereof, of which the following is a specification, reference being had to the accompanying drawing, forming a part thereof.

Fig. 2 is a top view of a protector for a nursing bottle and nipple thereof.

I claim:

The ornamental design for a protector for a nursing bottle and nipple thereof substantially as shown.

JOSEPH SCHNEIDERMAN.
